HEADLIGHT

John Jackson, Warren, Ohio

Application July 26, 1932. Serial No. 624,830

1 Claim. (Cl. 240—41.3)

This invention relates to headlights and has for the primary object, the provision of a device of the above stated character which is so constructed as to reflect light rays therefrom capable of illuminating a maximum distance without substantial glare.

With this and other objects in view, this invention consists in certain novel features of construction, combination and arrangement of parts to be hereinafter more fully described and claimed.

For a complete understanding of my invention, reference is to be had to the following description and accompanying drawing, in which

15 Figure 1 is a front elevation illustrating a headlight constructed in accordance with my invention.

Figure 2 is a sectional view taken on the line 2—2 of Figure 1.

20 Figure 3 is a fragmentary sectional view taken on the line 3—3 of Figure 2.

Figure 4 is a plan view illustrating a supporting bracket.

Referring in detail to the drawing, the numeral 25 1 indicates a tubular casing having mounted therein spaced rings 2, one of which is detachably secured to the casing as shown at 3 and provided with an annular flange 4. The rings 2 form seats for lenses 5. The casing 1 between the lenses is 30 mirrored to provide cylindrical reflecting surfaces. A hood 6 is detachably secured in one end of the casing 1 and is provided with a flange 7 to force a gasket 8 against one of the lenses. The other

lens is forced against the gasket 9 which in turn bears against the flange 4 by a spacing ring 10 engaged by a reflector 11. The reflector 11 carries an annular collar 12 threaded in the casing 1. The reflector 11 supports an electric lamp 14 in 60 close proximity to the innermost lens and centrally thereof.

Brackets 15 are secured to opposite walls of the casing 1 between the lenses and have pivoted thereto split collars 16 to surround the necks 17 65 of transparent containers 18 filled with a clear liquid or water. The containers depend downwardly from the brackets within the casing and converge toward each other as shown in Figure 1.

While I have shown and described the preferred embodiment of my invention, it will be understood that minor changes in construction, combination and arrangement of parts may be made without departing from the spirit and scope of my invention, as claimed.

Having thus described my invention, what I claim is:—

A headlight comprising a casing, a reflector located in one end of the casing, spaced lenses mounted in the casing, said casing having a mirrored surface between the lenses, adjustable brackets secured to opposite sides of the casing between the lenses, and transparent containers secured to the casing by the brackets and depending downwardly therefrom and converging toward each other and containing liquid.

JOHN JACKSON.
